UNITED STATES PATENT OFFICE.

JOSEPH A. WELSH, OF DUNKIRK, NEW YORK.

HEATING APPARATUS.

Application filed May 3, 1923. Serial No. 636,460.

This invention relates to heating apparatus and particularly to steam and hot water heaters, the main object of the invention being to provide simple, reliable and efficient means for increasing the heating efficiency of such types of heating apparatus, and especially for utilizing a greater proportion of the heat from the products of combustion.

A further object of the invention is to provide a novel construction of means for more efficiently utilizing the heat of the products of combustion which may be, with equal efficiency, applied to new boilers or boilers already installed and in use.

The invention consists of the features of construction, combination and arrangement of parts, hereinafter fully described and claimed, reference being had to the accompanying drawings, in which:—

Figure 1 is a side elevation of a heating apparatus constructed in accordance with my invention.

Figure 2 is a front elevation of the same.

Figure 3 is a vertical transverse section 25 through the smoke-box taken on the line 3—3 of Figure 1.

Figure 4 is a horizontal section taken on the line 4—4 of Figure 3.

Figure 5 is a vertical longitudinal section 30 taken on the line 5—5 of Figure 4.

Figure 5^a is a cross-section through the body of the heater.

Figure 5^b is a vertical longitudinal section of the same on line 5^b—5^b of Figure 5^a.

Figure 6 is a view similar to Figure 5 showing a modified construction.

Figure 7 is a vertical transverse section on the line 7—7 of Figure 6.

Figure 8 is a vertical front-to-rear section 40 through the smoke-box portion of another modified form of the invention.

Figure 9 is a horizontal section on line 9—9 of Figure 8.

Figure 10 is a perspective view of a header or rear boiler section which may be used in place of that shown in Figures 8 and 9.

Figure 11 is a horizontal section through a portion of a boiler showing a mode of supporting the flue partition plates.

Figure 12 is a vertical transverse section 50 through one side of the furnace showing the use of brickwork flue partitions.

Figure 13 is a view similar to Figure 1, showing a modification in the wall construction of the furnace.

55

Referring now more particularly to Figures 1 to 5^b, inclusive, of the drawings, 1 designates the usual boiler shell or casing, including in its organization any preferred type and arrangement of fire-box, ash-pit, 60 and water heating or steam generating chamber or space, a boiler of oblong rectangular form being shown in the present instance in which 2 is the fire-box containing water heating coils or elements 3 and a grate 3^a. The internal construction of the heater may be of any ordinary or suitable type such as is commonly used in steam or hot water heaters and, while the invention is shown in the present instance as applied to a heater 70 of rectangular type, it is to be understood that it may be applied to a heater of round or any other suitable form.

In carrying my invention into practice, I provide a brickwork setting or enclosing casing 4 for the boiler shell or casing 1, which setting 4 preferably encloses the shell 1 at all points except the front, leaving the front wall 5 of the shell exposed, or in practice all of this front wall 5 except the usual openings and doors therein may be covered by the brickwork. In the present instance, however, I have shown the wall 5 fully exposed and said wall is provided with a desired number and arrangement of clean-out doors 6, a fire-door 7, a clinker-door 8 and an ash-pit door 9, arranged to normally cover suitably provided openings in the wall 5.

The setting 4 includes, preferably, a solid base portion 10, built up to the line of the bottom of the ash-pit, a top wall 11, side walls 12, and a rear wall 13, the said side walls 12 and the rear wall 13 being spaced from the similar walls of the shell 1. The spaces between the side walls of the shell 1 and the side walls 12 of the setting provide intervening longitudinal flues or passages 14, while the space between the rear wall 13 of the setting and similar wall of the shell 1 provides a smoke-box 15 communicating at its sides with the rear ends of the flues 14. The flues 14 and 15 may be of any suitable width and are preferably coextensive in depth with the side and rear

75

100

walls of the boiler shell and are sub-divided, as hereinafter described, to secure a prescribed flow of the smoke, gases and other products of combustion from the fire-box 5 prior to the exhaust of such products of combustion through an outlet pipe 16 communicating with the smoke-stack.

Arranged within the smoke-box 15 is a header formed of cast iron or other suitable 10 material and comprising a vertically disposed body plate 17 of a length coextensive in length and depth with the smoke-box and which preferably forms a liner for the rear wall 13 of the setting 4. This plate 17 is 15 provided with a bottom flange or plate portion 18 resting on the bottom wall of the smoke-box, and it is also provided with a preferably arched top flange or plate 19 which lines the top wall 11 of the brick 20 setting and forms a support therefor, the two flanges 18 and 19 serving to firmly set or anchor the header in position.

The header is formed with a substantially 25 central partition 20, of approximately arched formation, and including downwardly and outwardly inclined flanges or walls 21, covering the space between the same and the rear wall of the shell 1 and extending outwardly to the lines of the side walls of 30 the shell defining the inner walls of the flues 14. This partition 20, so formed by the walls or flanges 21, separates the smoke-box into lower and upper chambers or compartments 22 and 23. The compartment 22 35 communicates with the smoke outlet from the fire-box in the rear wall of the shell 1 through a primary smoke outlet flue 24, which is located immediately below the upper central portion of the partition 20, 40 while the compartment 23 communicates at its top with the final outlet flue or pipe 16 which communicates in practice with the chimney or smoke stack, and which may be formed as part of the wall or flange 19. 45 In this pipe or flue 16 is placed a suitable damper 25 whereby the draft through the heater and between the same and the chimney or stack may be controlled. The cast iron header 17 may be fixed in position by 50 its parts bearing against the portions of the brickwork and also by the use of four or more standard bolts or nipples 26 which may be set in the brickwork and also connect the header with and hold it in fixed 55 relationship to the rear wall of the boiler shell.

The partition plates 21, which also serve the function of deflectors, are integral at 60 their outer edges with partition plates 27, which partition plates 27, as shown particularly in Figure 5, extend longitudinally within the flues 14, said plate 17 terminating in rear of the front walls of the flue and forming upper and lower channels 28 and 65 29 communicating at their forward ends

with each other through a vertical cross passage 30. The crown portion of the partition 20 is formed to provide a guideway for a sliding damper plate 31 for controlling an opening 32 therein, which damper 31 is provided with an operating rod or handle 33 extending to the exterior of the boiler whereby it may be manipulated. This damper may be entirely closed to cut off communication between the chambers 22 and 23, fully 70 opened to form a direct passage through the opening 32 for the products of combustion from the outlet 24 from the chamber 22 to the chamber 23, or partially closed to regulate the amount of the products caused to circulate through the flues 14 before passing to chamber 23 and the amount of the products of combustion which are allowed to pass directly from outlet 24 to the chamber 23 and thence to the final smoke 75 outlet 16. With the construction shown, it will be seen that when damper 31 is fully closed, the products of combustion discharging through the outlet 24 will be directed by the plates 21 downwardly and laterally into the rear ends of the flue channels 28 and caused to flow forwardly through said channels and up through the cross passages 30 into the channels 29 and thence backward through said channels 29 into the compartment 23, before discharging through the smoke outlet 16, their rapidity of flow and freedom of discharge being governed by the setting of the damper 25. Hence it will 80 be understood that the smoke, gases and other products of combustion which ordinarily pass directly outward to the stack may be caused to circulate across the back of the boiler shell and along the sides of said shell through a circuitous course, whereby all of the available heat therefrom will be utilized before such products finally discharge through the outlet 16 into the stack, whereby greater economy of fuel and efficiency of heating action will be secured. 85 It is to be understood, however, that when conditions require, as when a fresh fire is started, both dampers 31 and 25 may be partially or fully opened to promote the draft and until the fire has gained full headway, when the damper 31 may be closed and the damper 25 arranged as required to cause the products of combustion to flow around the shell before discharging as above described. It will therefore be apparent 90 that the damper 31 may serve as a direct or indirect damper to control the flow of the products of combustion between the fire-box and the outlet 16 as may be required at different times in the operation of the heater.

In order to secure still greater efficiency of operation, I provide in the lower chamber 22 of the smoke box a vertical partition 34 of substantially triangular or pyramidal form in cross-section and which extends 95

from the base 18 upwardly to the bottom of the flue 24. This partition 34 sub-divides the compartment 22 into a pair of side compartments 35, and its sloping sides cooperate with the inclined partition walls 21 to cause the products of combustion issuing from outlet 24, when damper 31 is partially or fully closed, to be separated into oppositely flowing streams of substantially equal volume passing to the opposite sides of the smoke-box and into the flues 14, thus ensuring even and regular division of the heat to the different portions of the shell. The partition 34, furthermore, is preferably made in the form of a hollow casting providing a water coil or chamber auxiliary to the water or steam chamber 3 and communicating with a primary (feed) inlet 36 and with the rear coil 3 through a desired number and arrangement of circulating tubes 36^a for the flow of relatively cool water from the main water chamber to the coil or auxiliary water chamber and the back-flow of the hot water heated thereby or steam generated thereby into the coils 3, the said coil 34 being intensely heated by the hot products of combustion flowing against its side and which are thereby utilized as a means for heating a portion of the water or promoting the generation of steam. The element 34 thus serves, as will be understood, the triple function of a partition, deflector and water coil for the purposes described. Openings, closed by doors 37, are provided at the front of the heater to permit ready access to the flues 14 for cleaning out purposes, and openings closed by doors 38 are provided in the side walls of the heater to permit convenient access to the chambers 22 and 23 of the heater for cleaning out purposes, such arrangement of cleaning out openings affording ready and convenient access to the flues and chambers for the removal of deposits as well as to permit repairs when occasion requires. At the points where the doors 38 are arranged the partitions 27 extend outward to the line of these doors.

In Figures 6 and 7 I have shown a slight modification in the construction of the heater, and particularly in the formation of the side flues 14', whereby a greater number of flow channels are formed and the products of combustion caused to pass back and forth a greater number of times before discharge. As shown, the header 17 is here provided with a pair of superposed forwardly extending partitions 27' terminating short of the front wall of the header and leaving cross passages 30', while an intermediate partition 27^a is supported either from the brickwork or side wall of the shell between the partitions and extends from the front wall rearwardly and terminates short of a wall 39 to provide a cross passage 30^a. Wall 39 provides here a vertical partition closing com-

munication between the rear ends of the intermediate channels formed by the longitudinal partitions and the chamber 23, so that four channels 29' are formed to cause the products of combustion to pass a corresponding number of times back and forth through the flues 14 before passing into the chamber 23 and thence discharging through the outlet 16. It will of course be understood that any number of such horizontal partitions may be provided to produce any number of channels to increase the course of flow of the circulating products of combustion as may be required dependent upon the size of the heater and the degree of heating efficiency which it is sought to obtain.

In Figures 8, 9 and 10, I have shown a modification particularly in the construction of the header whereby the rear wall 13, as such, may be omitted, its place being taken by the modified header. As shown, this header 17' is in the form of a hollow casting, conforming to the outline shape of the furnace body and which rests at its base upon the base portion 10 of the setting and is arranged with relation to the rear wall of the furnace body to form the rear smoke-box or chamber in the same manner as previously described. This cast iron header comprises outer and inner spaced body plates 40 and 40', and bottom, top and side walls 41, 42 and 43, respectively, having flange extensions 41', 42' and 43' projecting inwardly beyond the plate 40', the flanges 42' and 43' partially overlapping the side and top walls of the outer casing and spacing the body plates 40' therefrom to form with the rear wall of the furnace body the smoke chamber or compartment described. The partitions 21 and hollow cast metal header, and the side flanges 43' of said header are provided with cut away portions 44 to form the clean-out openings closed by the doors 38. The flange 42' of this heater and adjacent surface of the rear boiler section in advance thereof are formed with semi-circular recesses to cooperatively provide a smoke outlet, in which a smoke pipe 16 and its damper 25 of approved construction may be fitted. The spaced walls or plates 40 and 40' in this heater provide a water heating or steam generating compartment 17^a, forming a water-way section constituting a part of the steam generating system of the boiler for a steam job or a part of the water circulating system for a hot water job. Such new rear boiler section may take the place of the rear section of an old boiler and serve its function as well as to provide the improved features heretofore described. As shown, with this construction the partition member 34^a is solid and may be bolted to the boiler section ahead, or with compartment 17^a of the rear boiler section 17', or with both. The

section 17' is fastened to the adjacent back section of the boiler by four upper and lower hollow bolts or tubes 26' which serve as conductors, the two upper tubes connecting the steam spaces and the two lower tubes the water spaces for circulation of steam and water in a steam heating system and all four tubes serving to maintain a continuous water circulation in a hot water heating system. 10 Screw thread or push nipple joints may be used on all four hollow bolts or tubes to join the two rear boiler sections together. The section 17' as thus constructed will add materially to the rating of either the steam or the hot water boiler to which it is applied by increasing the steam generating or water heating and circulating space, as well as by utilizing generally heat ordinarily allowed to go to waste, as will be readily understood. 15

20 In Figure 11 I have shown another modification which may be employed, when it is desired to use flue partition plates formed separately from the header. As shown therein, I provide supports for the partition plates in the form of bolts 46, one of which is shown, each bolt having an elongated head 47 at its inner end, for passage through a similarly shaped slot in the connecting web between adjacent sections of the boiler structure. This bolt 46 is passed inwardly through an opening 49 in the side wall of the outer casing with the head 47 turned parallel with the slot 48, and then the bolt is given a quarter turn to bring the head 47 transversely of the slot, thus locking the bolt in place. The outer end of the bolt is threaded to receive the outer end of a nut 50 with which may be associated a washer 51, the construction being such that when the nut is fully screwed up the bolt will be held firmly in position. Bolts thus applied may be employed at suitable distances apart to form supports on which the partition plates may rest, and the bolts incidentally serve as stays to connect and increase the strength and durability of the boiler structure and outer enclosing casing. 30

35

40

45

50 In Figure 12 I have shown another modified form of the invention as applied to the construction of the flue partitions, in which, for example, a partition 27' is shown made of brickwork or its equivalent and which method of construction may be used in forming any or all the flue partitions in lieu of the use of partitions made of cast iron, steel or other metal. 55

55 In Figure 13 I have shown a modification in the wall construction of the furnace, this view being sufficient to indicate a construction which may be carried on throughout. As shown therein, a metallic corner framing 52 is provided consisting of angle iron side and top bars which extend around the front and side walls and front

and top walls of the outer casing at the corner angles or points of juncture of such walls and overlie brickwork material 53 employed as a filling in the wall construction, in this instance the front wall. 70 Extending down the front of the furnace are also metal strips 54, which may be suitably anchored at their base and riveted or otherwise secured to the top strip 52 and which are disposed in parallel relation to the side strips 52. These intermediate vertical strips 54 overlap the adjacent edges of the brickwork filling 53 and form jambs for a central wall section 55 of metal or other suitable material, in which are formed the flue and door openings and which supports the flue, fire and ash-pit doors. The metallic parts described provide an external frame for reinforcing the boiler and to form component parts of an exterior frame, and this structure may be employed throughout the formation of all the exterior walls of the furnace. Bolts 56 may be provided to connect the metallic frame elements specified to the inner casing or boiler structure. The 80 brick-work filling 53 may be provided with openings to receive the flue door frames 37' forming the flue openings closed by the doors 37a. This type of structure may be used whenever it is desired to provide an external casing of reinforced type and made to a greater or less extent of brick and a metallic bracing frame structure. 85

90

95

100 From the foregoing description, taken in connection with the drawings, it will be seen that my invention provides a heater, equally applicable to hot water or steam heating furnaces, which furnishes auxiliary heating surfaces and means for directing the flow of the products of combustion in an effective manner to enable all of the available heat to be abstracted therefrom before the discharge of such products to the stack. By this means a large proportion of the heat which goes to waste, in heaters of ordinary construction, may be utilized for heating purposes, ensuring greater heating efficiency as well as a substantial economy in the use of fuel. Furthermore, the invention provides a means whereby an additional volume of hot water may be furnished or steam produced for heating or other purposes. The principle of the invention may, obviously, be applied to new heaters to be installed or to old heaters already installed 110 without variation in the construction of the heaters as commonly used, and through the simple building of the brick setting and installation of the parts cooperating therewith, the outer surface of the heater shell being utilized to form the inner walls of the additional heat circulating chambers and to be heated by the products of combustion flowing in contact therewith, the construction described therefore allowing old fur- 115

120

125

130

naces to be converted to give greatly increased heating efficiency. A material advantage incident to my construction is that the additional parts may be applied at a 5 comparatively low cost, to steam and hot water heaters of all types, without the necessity of making any changes of importance in the construction of the heater itself.

Having thus fully described my invention, I claim:

1. The combination with a heater including a shell having a fire-box provided with a smoke outlet, of an outer casing enclosing the sides and rear of said shell and forming therewith intervening longitudinal side flues and a rear transverse smoke-box, said shell being provided also with a water chamber, a header in said smoke-box provided with an upper chamber communicating with 15 the outlet ends of the flues and having a final smoke outlet and a lower chamber communicating with the inlet ends of the flues and having a smoke inlet communicating with the smoke outlet of the fire-box, a hollow partition within the lower chamber of the header sub-dividing said chamber into 20 separate side chambers below the smoke inlet, said hollow partition forming a water heating chamber, and connecting means between said water heating chamber and the water space of the shell.

2. The combination with a heater including a shell having a fire-box provided with a smoke outlet, of a casing enclosing 25 the sides and rear of said shell and forming therewith longitudinal side smoke flues and a rear transverse smoke-box, said flues having inlet ends and exhaust ends, a header within the smoke-box provided with a partition separating the same into an upper chamber communicating with the exhaust ends of the flues and a lower chamber communicating with the inlet ends of the flues, said partition including deflector walls inclining toward said flues and having an opening therein, a sliding damper controlling said opening, a smoke outlet from the upper chamber, a smoke inlet in the lower chamber communicating with the smoke 30 outlet of the fire-box, a final smoke outlet from the upper chamber provided with a controlling damper, and a vertical partition in the lower chamber sub-dividing said chamber into side compartments, said partition being hollow and forming a water chamber, and means for connecting said water chamber with a portion enclosed in the heater shell.

3. The combination with a heater including a shell having a fire-box and a smoke outlet, said shell comprising hollow water containing sections, of a smoke-box forming header at the rear of the shell, said header being provided with a water compartment 35 communicating with the water compartment

of the rear section of the shell, and said header having a flange which together with the shell subdivides the smoke-box into upper and lower chambers, the lower chamber communicating with the smoke outlet of the shell and the upper chamber having a smoke outlet to a stack, and a casing enclosing the smoke-box and at least the sides of the shell and forming with the sides of the shell passages for the flow of the products of combustion from the lower chamber of the smoke compartment around the sides of the boiler and thence back to the upper chamber of said smoke compartment and finally through the smoke outlet thereof.

4. The combination with a heater including a boiler shell having a fire-box and a smoke outlet, of a header at the rear of the boiler shell and forming therewith a smoke-box, said header being subdivided to provide upper and lower compartments, said smoke outlet communicating with said header for the discharge of the products of combustion therefrom into the lower compartment near the upper portion thereof, a member in the header having deflecting surfaces for dividing the products of combustion and deflecting the same laterally in both directions, a tortuous passage connecting the lower and upper compartments of the header and extending back and forth longitudinally of the boiler shell at each side thereof for causing the products of combustion flowing through the passage to contact with such side of the boiler shell, and a valve to permit the products of combustion to flow from the lower to the upper compartments without taking said tortuous passage.

5. The combination with a heater; of a header to be attached thereto, said header being subdivided longitudinally to provide upper and lower compartments, the lower compartment adapted to receive the products of combustion from said heater, a partition in said header having deflecting surfaces to direct said products laterally in equal volume and in downward direction, a tortuous passage extending alongside a surface of the boiler shell and connecting the lower compartment with the upper, and a valve controlling direct communication between said compartments and arranged to permit products of combustion to pass to the upper compartment without contacting said partition or taking said tortuous course.

6. The combination with a water heater; of a header to be connected therewith, a horizontal partition in said header dividing the same into upper and lower compartments, a passage in the upper part of the lower compartment whereby products of combustion pass from said heater to said lower compartment, a hollow partition in said header forming a water chamber arranged in said lower compartment immediately below said

passage and having deflecting surfaces to divide the products of combustion and to deflect the same downwardly and laterally in equal volume, a tortuous passage extending alongside a surface of the boiler shell and establishing communication between said upper and lower compartments, a wa-

ter chamber in said partition immediately above said valve, and the said hollow partition adapted to be connected to the water containing space of said heater.

5 In testimony whereof I affix my signature.

JOSEPH A. WELSH.
